UNITED STATES PATENT OFFICE.

JOHN G. GRANBERG, OF BECKEMEYER, ILLINOIS.

CONDENSER FOR REDISTILLING SPELTER.

1,221,045.

Specification of Letters Patent.

Patented Apr. 3, 1917.

Application filed December 6, 1916. Serial No. 135,852.

To all whom it may concern:

Be it known that I, JOHN G. GRANBERG, a citizen of the United States, and resident of Beckemeyer, Illinois, have invented certain 5 new and useful Improvements in Condensers for Redistilling Spelter, of which the following is a specification containing a full, clear, and exact description, reference being had to the accompanying drawings, forming 10 a part hereof.

My invention relates to improvements in condensers for redistilling spelter and the object of my improvements is to provide a condenser of simple and inexpensive construction having a continuously open charging and venting opening, a relatively small drawing opening in which a stopper is employed which is impervious to the metal and a fixed bridge at its retort end.

Condensers as are in common use are provided with a discharging mouth, arranged to be stoppered to hold metal in the condenser; by coal screenings, which completely close the condenser against the escape of 25 gases which not infrequently attain pressures which the condenser is not capable of withstanding and which condition adds an element of danger to their use.

The coal screening stopper is objectionable in that it causes a loss of production by taking up metal, the recovery of which requires a separate and more or less expensive operation. The coal screening stopper is further objectionable in that in a service 35 of five or six days it causes the condenser mouth to grow shut and inoperative.

The condenser constructed according to my invention eliminates the use of the coal screening stopper and its consequent loss of 40 production as well as its tendency to cause the mouth to grow shut and in having the charging opening continuously open the annoyance and danger incident to the gases is obviated.

For the above purposes my invention consists in certain novel details of the construction of the condenser and its arrangement and combination with the retort as will be 45 fully, clearly and concisely set forth in my specification pointed out in my claims and 50 illustrated by the accompanying drawing in which—

Figure 1 is a longitudinal sectional elevation showing my improved condenser and 55 its relation to a retort and furnace, and

Fig. 2 is an end view of the condenser.

Referring by numerals to the drawings, 5 designates the furnace which is of the type known as Belgium furnaces, and of which only a portion is shown.

At intervals throughout its height the rear wall, that is the wall at the left hand side of Fig. 1 of the drawings, is provided with bricks 6 which extend inwardly from the wall proper to provide supports for the rear 65 or inner ends of the retorts 7.

In the front wall of the furnace, in number and arrangement similar to the bricks 6, there are the openings 8 through which the retorts are inserted and in which the forward or outer ends of the retorts are supported.

In order to support the retorts at an incline with relation to the horizontal the openings 8 are disposed in a plane somewhat 75 higher than the bricks 6, as is common.

While the drawing shows one only of the retorts and a fragment of a second retort it is to be understood that the entire furnace comprises a plurality of such retorts arranged usually in superposed rows.

The retorts are constructed of ceramic material and by preference of substantially cylindrical formation, their rear or inner ends being closed by an integral head 9 and 85 their forward or outer ends 10 being open.

It is to be observed from Fig. 1 that the end 10 is not, in its entirety at right angles to the axis of the retort, but that a portion 11 thereof extends beyond the body of the 90 retort and that the connecting line between said extended portion and the body is arcuated.

The numeral 12 designates the condenser, which is constructed of ceramic material, of 95 substantially cylindrical formation, and of a slightly lesser diameter than the retort, and has at its rearmost end an integral bridge wall 13 whose lower inner face is shaped to conform with the outer end 10 and the arcuated portion 11 of the retort. This construction provides a simple non-leaking joint between the retort and the bridge of the condenser as well as a means for preventing relative rotational movements between the 100 retort and condenser.

The rear end of the condenser diametrically opposite the bridge, is provided with a downwardly and rearwardly projecting flange 14 which serves the double function of 110 fitting into the end of the retort to make a vapor tight joint and providing a lip

which breaks the otherwise continuous overhead line of the retort and condenser to the end that distillate will not be carried along the overhead line to the outer open end of 5 the condenser. This inner end of the condenser is open except for the bridge and the flange.

At the outer end of the condenser there is a head 15, preferably formed integrally 10 with the condenser, which only partially closes the end of the condenser (as shown in Fig. 2) leaving an opening 16 through which the retort may be charged and which also provides a vent for gases incident to 15 the distillation.

Diametrically opposite the opening 16 there is formed through the head 15, an opening 17 which aligns with the inner surface of the condenser whereby the distillate 20 may be drawn from the condenser.

Into the opening 17 there is fitted a ceramic plug 18 which is incapable of "taking up" the metal as is common with the stoppers formed of hard coal screenings and 25 hence eliminates the loss in production, in this particular.

The operation of distillation of my apparatus is substantially the same as the ones now in use except for the charging and 30 drawing.

In the employment of my device the raw metal is first formed into zinc strips about 30 inches long, about 2 inches wide and weigh in the neighborhood of 12 pounds, 35 these strips are inserted through the opening 16 of the condenser and through the open end 10 of the retort over the bridge wall 13, and placed in the retort containing the molten metal. These metallic bars are 40 melted in the retort and the refined metal passes over the bridge 13 and settles in the condenser until time for drawing; the drawing is then accomplished by removing

the ceramic plug 18, the refined metal then flowing freely into the ladle.

45

As heretofore stated the old condensers employed a stopper of hard coal screenings, which completely closed the condenser and made it impossible to charge while drawing.

In my condenser the opening 16 may be 50 employed at all times for charging even while the metal is being drawn.

Having thus described my invention, what I claim is:—

1. A condenser having a fixed head provided with a series of openings at its drawing end.

2. A condenser constructed of ceramic material having an integral head at its drawing end, there being a continuously open charging and venting opening in said head, and a drawing opening in said head, and a ceramic plug for said drawing opening.

3. A condenser constructed of ceramic material having at its retort end an integral bridge and a down turned flange, and at its drawing end an integral head, there being charging and drawing openings formed in 65 said head and a ceramic closure for said drawing opening.

4. In combination with a retort, a condenser having at its retort end a fixed bridge and a downturned flange arranged to prevent leakage between the abutting ends of the retort and condenser, and said condenser 75 having a fixed head at its drawing end provided with a drawing opening and a charging opening.

In testimony whereof, I have signed my name to this specification, in presence of 80 two subscribing witnesses.

JOHN G. GRANBERG.
